To all whom it may concern:

Be it known that I, Herman Neuwirth, a citizen
of the United States and a resident of the Bor-
ough of Brooklyn, county of Kings, city and
State of New York, have invented a new, orig-
inal, and ornamental Design for a Barometer
Tube, of which the following is a specification,
reference being had to the accompanying draw-
ing, forming a part thereof, wherein

Figure 1 is a top plan view of a barometer
tube showing my new design;

Figure 2 is a side view, and

Figure 3 is a front view.

I claim:

The ornamental design for a barometer tube, as
shown.

HERMAN NEUWIRTH.
